THREAD PROTECTOR

Theodore R. Thoren and Bill C. Bredenbeck,
Cleveland, Ohio, assignors to Thompson Products Incorporated, Cleveland, Ohio, a corporation of Ohio

Application February 27, 1942, Serial No. 432,634

(2) Claims. (Cl. 133—96)

This invention relates to an inexpensive protector for internally threaded or otherwise internally grooved members.

More particularly the invention relates to a cover or shield for internally threaded parts which has a deformable disk member with an inwardly projecting cut to define a leading edge adapted to enter the groove of a thread and effect deformation of the periphery of the disk in accordance with the pitch of the thread to lead the entire peripheral edge of the disk into the groove of the thread.

Many internally threaded parts must be protected in shipment from ingress of dirt and the like. Metal plugs have been used for such purpose but the same are expensive and are apt to mar the internal thread or leave metal particles which would interfere with the proper working of internal parts. Cork plugs are apt to leave cork particles in the thread where they will later cause difficulties. Rubber plugs will soften and swell if the internally threaded parts contain gasoline, oil or grease. The swollen or deteriorated rubber will gum up the threads. Plugs of artificial rubber which are not affected by hydrocarbons such as gasoline or oil are very expensive and may slough off in the thread. Further, some types of plugs are subject to cold flow. The resilient portion of the plug then relaxes its grip on the thread and the plug drops out.

In accordance with this invention, inexpensive thread protectors, covers or shields are now made from fiber board, cardboard, or similar cheap fibrous material. In one modification of the invention a fiber board disk is merely provided with an inwardly extending cut to form a leading edge adapted to enter the groove of a thread so that the rest of the periphery of the disk will follow the leading edge into the groove, upon relative rotation of the disk and internally threaded member. The peripheral edge of the disk will be deformed in accordance with the pitch of the thread.

In another embodiment of the invention the thread-engaging disk can be in the form of a frusto-cone and carry a cover member on the small end thereof. The frusto-conical thread-engaging member is radially cut to provide the leading edge which will draw the periphery or base of the cone into the threaded opening until the cover portion engages the mouth of the opening. The cover portion can be connected to the conical portion by means of any suitable fastening means such as, for example, an inexpensive wire staple.

It is, then, an object of this invention to provide a shield for an internally grooved member adapted to enter the internal groove for closing an opening in the member.

A further object of this invention is to provide a protector for internally threaded ports.

Another object of the invention is to provide an inexpensive thread protector made of fiber board or the like non-metallic fibrous material.

Still another object of the invention is to provide a shield for internally threaded parts including a cover member for the mouth of the threaded opening in the parts and a conical thread-engaging member for drawing the cover member tightly against said mouth.

Still another object of this invention is to provide a disk-type thread protector having a screwdriver slot therein to facilitate rotation of the member into a threaded opening.

Other and further objects of the invention will become apparent to those skilled in the art from the following detailed description of the annexed sheet of drawings which, by way of preferred examples, illustrate two embodiments of the invention.

On the drawings:

Figure 1 is a side elevational view, with parts broken away and shown in vertical cross section, of an airplane engine fuel pump having the internally threaded ports thereof closed with one form of thread protector according to this invention.

Figure 2 is an enlarged bottom plan view of one of the thread protectors shown in Figure 1.

Figure 3 is a cross-sectional view of the thread protector taken along the line III—III of Figure 2.

Figure 4 is an exploded side elevational view of the parts of the thread protector shown in Figures 1 to 3.

Figure 5 is a top plan view of another form of thread protector according to this invention.

Figure 6 is a cross-sectional view taken along the line VI—VI of Figure 5.

As shown on the drawing:

The reference numeral 10 in Figure 1 designates generally an airplane engine fuel pump having internally threaded ports 11. In accordance with this invention, fiber board thread protectors 12 are provided to close the ports 11 during shipment of the pump 10. These protectors 12 will satisfactorily seal the ports 11 against ingress of dirt, will not leave any foreign material in the ports, are readily insertible and removable from the ports, and are sufficiently inexpensive so that they may be discarded after a single use, although they are capable of being used many times. The protectors are merely inserted into the ports at the manufacturing plant and being composed of inert material such as pressed fiber board they will not be affected by any gasoline, oils or greases in the pump parts.

As shown in Figures 1 to 4 the thread protector 12 is composed of a flat fiber board disk 13 serving as a cover member adapted to seat

on the mouth of a port 11. The cover member 13 has an elongated screwdriver slot 13a therethrough whereby a screwdriver may be readily inserted into the cover to rotate the protector into seated position in the threaded opening.

A frusto-conical or otherwise dished fiber board disk 14 of less thickness than the cover 13 has a flat head 14a at the apex thereof affixed to the center of the cover disk 13 by means of a metal staple or other fastener 15. The head 14a serves as a base which fits flat on the disk 13 and extends over the slot 13a to cover the slot.

The frusto-conical or otherwise dished member 14 has a peripheral edge 14b adapted to be seated in the groove of a thread.

The member 14 has a radially inwardly extending cut 14c extending from the edge 14b to the flat head or base 14a. This cut 14c provides a leading edge 14d to the groove-engaging periphery 14b. The leading edge 14d is readily insertible in the groove of a thread and will draw the rest of the peripheral edge 14b into the groove of the thread as the protector is rotated. The member 14 is sufficiently flexible so that the peripheral edge 14b thereof will flex into conformity with the pitch of the thread with the result that after the peripheral edge 14b has been completely seated in the groove of the thread the leading edge 14d is one thread ahead of the trailing edge 14e. The leading and trailing edges 14d and 14e are thus spaced apart the distance of one screw thread.

The dished member 14 is preferably somewhat resilient so that the leading and trailing edges 14d and 14e tend to somewhat reclaim their original aligned position and thereby cause the peripheral edge 14b to grip the thread in which the edge is seated. This gripping action maintains the protector in seated position and prevents accidental displacement of the protector.

The staple 15, as shown in Figure 4, may have pointed ends 15a adapted to be forced successively through the head 14a of the member 14 and thence through the disk 13. The legs of the staple are then bent outwardly as shown in Figures 1 and 3 over the outer face of the disk 13 away from the screw-driver slots 13a to retain the parts in affixed assembled relation. Alternatively, of course, holes could be provided through the head 14a and through the central portion of the disk 13 to receive a fastener, or the parts could be secured together in any other manner, as by means of a glue, bond, a rivet or the like.

In Figures 5 and 6 a second embodiment of the invention is illustrated. As therein shown a thread protector 16 composed of a substantially flat fiber disk 17 somewhat thicker than the member 14 of the protector 12 has the peripheral edge thereof beveled as at 17a to provide a thread groove engaging edge 17b. The disk 17 has a radial cut 17c extending inwardly from the peripheral edge 17b to define a leading edge 17d adapted to enter the groove of a thread and a trailing edge 17e adapted to be displaced from the leading edge 17d when the disk 17 has peripheral edge 17b thereof threaded into the groove of a thread.

The center of the disk 17 has a slot 17f therethrough receiving a metal cup 18 in tight engagement therewith. The cup 18 has an out-turned flange 18a engaging the top face of the disk 17 and when the flange 18a is engaged on

the outer face of the disk the cup projects somewhat inwardly from the inner face of the disk as best shown in Figure 6. The cup 18 defines a pocket 19 into which a screwdriver or other tool for rotating the disk can be inserted. Alternatively, of course, if the disk 17 is thick enough it could be scored partially therethrough to define the tool receiving recess.

If the disk is thin enough to define a peripheral edge which will fit into the groove of a thread, the same need not be beveled as at 17a.

The protector 16 shown in Figures 5 and 6 operates in the same manner as the member 14 of the protector 12. The protector 16, however, does not include a cover adapted to engage the mouth of a port but it is insertable into the groove of a thread and, when seated only in the outer groove of this thread, it will protect all the underlying inner structure of any internally threaded parts.

Both embodiments of the invention disclosed in the drawing are very inexpensive and are thus adapted for disposal after a single use.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. A thread protector adapted for closing the port of an internally threaded member which comprises a centrally apertured flat disk, a frusto-conical member having a head portion at the small end and smaller than the disk abutting one face of the disk and covering the aperture in said disk, means securing said head portion to the disk, said frusto-conical member having a cut extending inwardly from the base thereof along the side wall for an appreciable distance to provide a flexible tapering skirt having a deflectable base with a lead edge adapted for entering the groove of the thread in the internally threaded member to direct the base in said groove for drawing the disk against the mouth of the port, and said aperture in the disk cooperating with the head portion of the frusto-conical member to provide a closed bottom tool receiving recess.

2. A thread protector adapted for closing the mouth of an internally threaded member which comprises a substantially flat fibre board disk, a frusto-conical fibre member having a head wall at the small end thereof and a cut along the side wall thereof extending inwardly from the base thereof for an appreciable distance to provide a flexible skirt, said head wall being of smaller diameter than the disk, a wire staple securing the head wall to the central portion of the disk, said flexible skirt with the cut therein having a leading edge on one side of the cut and a trailing edge on the other side of the cut adapted to be offset from each other a selected amount for producing a self-adjusting thread groove engaging base edge on the skirt adapted to enter the thread groove of the internally threaded member and follow the pitch of the thread for drawing the disk against the mouth of the internally threaded member.
